UNITED STATES PATENT OFFICE.

EMIL R. DRAVER, OF RICHMOND, INDIANA, ASSIGNOR TO THE WOLF CO., OF CHAMBERSBURG, PENNSYLVANIA, A CORPORATION OF PENNSYLVANIA.

GRINDING-MILL.

1,097,010.

Specification of Letters Patent.

Patented May 19, 1914.

Application filed August 11, 1913. Serial No. 784,103.

To all whom it may concern:

Be it known that I, EMIL R. DRAVER, a citizen of the United States, residing in Richmond, in the county of Wayne and 5 State of Indiana, have invented certain new and useful Improvements in Grinding-Mills, of which the following is a full, clear, and comprehensive specification, being such as will enable others to make and use the 10 same with exactitude.

This invention pertains to certain specific improvements in cereal grinding mills, in which a compound scroll operates in conjunction with a fixed resistance-plate, to 15 provide the desired attrition upon the material acted upon.

The predominant and particular object of my present invention is to provide a series 20 of auxiliary blades to be employed in connection with the usual scroll heretofore employed, and to provide other minor improvements, all of which will be pointed out in the following specification.

The preferred means which I employ to 25 carry out my invention in a practical manner is shown in the accompanying drawings, in which—

Figure 1 is a side elevation of my mill, certain of the parts being shown in vertical 30 central section in order to exhibit interior mechanism. In said figure the normal position of the scroll or grinding blades is shown. Fig. 2 is similar to Fig. 1 in all particulars, except that it is taken from the 35 opposite direction and also showing another position of the scroll or blades. Fig. 3 is a cross section of the scroll hub, as taken on line 3—3 of Figs. 1 and 2, showing the relative positions of the auxiliary blades. And 40 Fig. 4 is a perspective view of one of the auxiliary blades alone.

Similar indices denote like parts throughout the several views.

In order that the construction, the operation, and the advantages of my invention may be fully understood and appreciated I will now take up a detailed description thereof, in which I will set forth the invention as comprehensively as I may.

Referring now to the drawings in detail, 50 numeral 1 denotes the pedestal or supporting frame, carrying on its upper end the relatively long horizontal bearing 2. Also carried by the pedestal 1 is the main casing 3, 55 which is round in cross section, that is at

right angles to the aperture in the bearing 2, and it is concentric therewith. Formed integral with the upper portion of the casing 3 is the inlet spout 4, by which inlet is obtained to the interior of the casing 3. One 60 end of the casing 3 is closed by the end 3', and the other end is partly closed by the tapering resistance plate 5, which latter projects outward convergently. Formed centrally through the outer end of the plate 5 65 is a round discharge aperture or mouth, as indicated at *a*, the same being concentric with the casing 3 and the bearing 2. Attached around the discharge mouth *a*, and carried by the plate 5, is the chamber 6, into 70 which the mouth *a* opens. Covering the top of chamber 6 is the sliding lid 7, and in the lower portion of chamber 6 is the exit *b*. Revolubly mounted in the bearing 2 and projecting at each end beyond said parts is 75 shaft 8. Rigidly mounted on shaft 8, near the bearing 2, is the drive-pulley 9.

Numeral 10 denotes a bearing secured to 80 the outer face of the chamber 6 and in which the shaft 8 is revolubly mounted. Numeral 11 denotes a stem which extends through the shaft 8. Secured on the end of stem 11, near the pulley 9, is the ball-bearing collar or head 12, the same being adapted to contact with that end of shaft 8. Threaded on the other end of the stem 11 is the adjusting wheel 13 carrying an inwardly directed disk 14.

Encircling the protruding portions of the 90 bearing 10, the shaft 8, and the stem 11, is the helical spring 15, same being seated against the flange 10 and the disk 14, and adapted to press outward.

The wheel 13 is adapted to be secured in 95 adjusted position by the locking wheel 16 which is also threaded on the stem 11.

Secured on shaft 8 and located inside the chamber formed by the casing 3 and the plate 5, is the hub 17. Extending out at 100 an angle, divergently, from the outer end of the hub 17, is the flange 18,—the periphery of the outer end of which is adapted to almost close the mouth *a*, as in Fig. 1. Radiating out from the hub 17, from the end 105 thereof opposite to the flange 18, is a plurality of blades 19 which collectively extend across the entire interior of the casing 3, as shown.

Extending inward from the inner face of 110

the plate 5 is a plurality of triangular lugs e, e', e'' and e''' , preferably four in number, which are adapted to prevent the material from slipping.

5 The operation of said parts is substantially as follows: The pulley 9 is to be revolved in any well known manner, and in the direction indicated by the arrows thereon, and this of course will revolve the shaft 8, the cone composed of the parts 17 and 18, and the blades 19. The spring 15 will normally retain the scroll in the position shown in Fig. 1, at which time the hub of pulley 9 will engage the outer end of the bearing 2 10 as shown. The material to be treated will enter the interior of the casing 3, through the inlet 4, from which it will be forced forward by the blades 19, and by which it is also disintegrated, the body of material being prevented from packing and sliding 15 around within the interior of plate 5 by reason of the lugs e, e', e'', e''' , the finished product being finally allowed to escape through the mouth a and around the periphery of the flange 18. From the chamber 6 the finished product may be conveyed 20 through the exit b to the point desired. The condition of the product may be examined 25 by opening the lid 7.

30 The most prominent feature of my present invention resides in the provision of a plurality of auxiliary trapezium-shaped blades 20, 21 and 22, each having a pair of ears: $f-f', g-g',$ and $h-h'$, respectively, each 35 ear having an aperture therethrough whereby the blades may be secured in position by means of screws, rivets, or the like. The positions of said blades 20, 21 and 22 are at an angle with relation to the flange 18 and 40 the hub 17, across which they are disposed diagonally, substantially as shown, same being located edgewise with relation to the surfaces of the hub 17 and the flange 18, and with the larger end of each of the auxiliary 45 blades located near to and parallel with the inner face of the resistance plate 5. By means of the auxiliary blades 20, 21 and 22 I have found that the capacity of the mill is materially increased and also the resultant 50 product is improved, as greater attrition is attained.

With my construction I find that it is practically impossible to choke or stall the mill by a plethora of material being delivered to the blades, for the reason that the scroll, or revolving cone and blades, is automatically adjustable to the proper compression with the resistance plate 5 and the discharge mouth a , the spring 15 at all time 55 compensating the load.

In practice I find it desirable to employ a less number of auxiliary blades than the number of relatively fixed blades; and also, as shown, the auxiliary blades are shorter than 60 are the fixed blades, they are also disposed

at a greater angle with relation thereto; also the auxiliary blades are spaced some distance from the fixed blades, being adapted to operate on the material after it leaves the fixed blades. The material referred to relates to cereals, particularly to wheat or its 70 derivations in the course of manufacture into flour or the like.

I desire that it be understood that various changes may be made in the several details 75 of construction herein shown and described without departing from the spirit of my invention or sacrificing any of the advantages thereof.

Having now fully shown and described my 80 invention, what I claim and desire to secure by Letters Patent of the United States, is—

1. A grain grinding mill having a grinding-chamber, a conical resistance plate carried by the discharge end of the said chamber, there being a comparatively large central aperture through the resistance plate, a shaft extending centrally through said chamber and said aperture, a hub secured on said shaft and located in said chamber, a flange 85 extending out divergently from the outer end of said hub with its periphery fitting said opening in the resistance plate, a plurality of angularly disposed blades arranged in a single row radiating from and formed 90 integral with said hub and extending across said chamber, a plurality of trapezium-shaped blades disposed diagonally across the periphery of said flange and a portion of the hub, a plurality of triangular lugs extending 95 from the inner face of the resistance-plate into the interior of said resistance plate, and means for laterally adjusting the hub and the parts thereto attached, all substantially as set forth. 100

2. In combination with a grain grinding-mill having a grinding chamber, a resistance plate of conical form closing one end of said chamber except for a central aperture therethrough, a shaft extending 110 through said chamber horizontally, a hub secured on said shaft, a plurality of blades located in a single row around and formed integral with said hub, the flange 18 flaring out from the discharge end of said hub with 115 its periphery fitting the aperture in the resistance plate, the trapezium-shaped blades 20, 21 and 22 removably secured diagonally across the inner face of said flange, and the triangular lugs e, e', e'' and e''' projecting 120 inward from the inner face of the resistance plate, all substantially as shown and described.

3. In combination with a grinding mill having a revolving scroll including a plurality of relatively fixed blades, a plurality of auxiliary blades carried by the scroll and being less in number than the number of fixed blades and also placed at angles different from that of the fixed blades and 125 130

adapted to operate upon the material after it has passed the fixed blades, all substantially as shown and described.

4. In a grinding mill having a grinding-chamber, a resistance plate extending out convergently with a central aperture therethrough, a shaft extending through said chamber and aperture, a hub mounted on the shaft, a flange carried by the hub and adapted to fit in said aperture, a plurality of fixed blades carried by the hub, and a plurality of auxiliary blades carried by the flange and adapted to operate upon the material after it leaves the fixed blades.

15 5. In a grinding mill having a grinding-chamber, a resistance-plate extending out convergently from said chamber and with a central aperture therethrough, a shaft extending through said chamber and aperture, 20 a hub mounted on the shaft, a flange extending out divergently from said hub and adapted to fit in said aperture, lugs extending inward from the resistance plate, a yielding tension normally retaining the 25 flange in said aperture, a plurality of auxiliary blades carried by said flange and dis-

posed at an angle different from the angle of the fixed blade.

6. In a grinding mill having a grinding-chamber, a conical resistance plate closing 30 one end of said chamber with a central aperture formed through the resistance plate, a shaft extending through said chamber and aperture in the resistance plate, a hub carried by the shaft and located in said chamber, fixed blades radiating from the hub, a flange carried by the hub and adapted to operate in said opening in the resistance plate, and a plurality of auxiliary blades secured diagonally across said flange with 35 their outer ends adjoining the outer edge of said flange and corresponding with the angle of the resistance plate, all substantially as shown and described.

In testimony whereof I have hereunto 40 subscribed my name to this specification in the presence of two subscribing witnesses.
